(57) CLAIM

The ornamental design for a shoe pendant, as shown and described.

DESCRIPTION

FIG. 1 is a perspective view of a shoe pendant showing an embodiment of my new design.

FIG. 2 is another perspective view of the shoe pendant of FIG. 1 worn on a shoe.

FIG. 3 is a front view of the shoe pendant of FIG. 1.

FIG. 4 is a rear perspective view of the shoe pendant of FIG. 1.

FIG. 5 is a rear view of the shoe pendant of FIG. 1.

FIG. 6 is a right side view of the shoe pendant of FIG. 1.

FIG. 7 is left side view of the shoe pendant of FIG. 1.

FIG. 8 is a top view of the shoe pendant of FIG. 1; and,

FIG. 9 is a bottom view of the shoe pendant of FIG. 1.

The broken lines in the figures show portions of the shoe pendant and/or environment that form no part of the claimed design. The break lines in FIG. 2 are used to show an area of enlargement depicting the shoe pendant in use and form no part of the claimed design.

While the accompanying drawings include broken lines that form no part of the claimed design, the broken lines provide written description of prospective embodiments that are claimed when one or more of the broken lines are amended to solid lines. Similarly, while the solid lines in the drawings form part of the claimed design, the solid lines provide written description of prospective embodiments that are not claimed when one or more of the solid lines are amended to broken lines.
